No. 40,013.

Specification for Design.

Patented May 25, 1909.

Application filed March 16, 1909. Serial No. 483,860. Term of patent 14 years.

To all whom it may concern:

Be it known that we, EDWARD G. SOLT-MANN, a citizen of the United States, residing at No. 125 East Forty-second street, in the borough of Manhattan, city, county, and State of New York, and ISO BILLIG, a citizen of Hungary, residing at 1482 Avenue A, in the borough of Manhattan, city, county, and State of New York, have invented a new, original, and ornamental Design for a Show-Card Blank, of which the following is a specification, reference being had to the accompanying drawing, forming part thereof.

The figure is an elevation of a show card
blank, showing my new design.

We claim:

The ornamental design for a show card
blank, as shown.

EDWARD G. SOLTMANN.
ISO BILLIG.
